UNITED STATES PATENT OFFICE.

ASA I. RABB, OF KANSAS CITY, KANSAS.

SWING.

1,155,439.

Specification of Letters Patent.

Patented Oct. 5, 1915.

Application filed May 25, 1914. Serial No. 840,883.

To all whom it may concern:

Be it known that I, ASA I. RABB, a citizen of the United States, residing at Kansas City, in the county of Wyandotte and State 5 of Kansas, have invented certain new and useful Improvements in Swings, of which the following is a specification, reference being had to the accompanying drawings.

This invention relates to certain improvements in swings and has relation more particularly to a device of this general character especially designed and adapted for use as a lawn swing; and the object of the invention is to provide a device of this type having novel and improved means whereby the same may be converted, with convenience and facility, from a swing into a bed or vice versa.

The invention consists in the details of 20 construction and in the combination and arrangement of the several parts of my improved swing whereby certain important advantages are attained and the device is rendered simpler, less expensive and otherwise 25 more convenient and advantageous for use, all as will be hereinafter more fully set forth.

The novel features of the invention will be carefully defined in the appended claim.

30 In order that my invention may be the better understood, I will now proceed to describe the same with reference to the accompanying drawings, wherein—

Figure 1 is an elevational view of a convertible swing constructed in accordance with an embodiment of my invention, the seat structure being adjusted for use as a swing proper; Fig. 2 is a view somewhat similar to Fig. 1, with parts broken away 40 and the device adjusted in position to be used as a couch; and Fig. 3 is a sectional view taken substantially on the line 3—3 of Fig. 2.

As disclosed in the accompanying drawings, 45 1—1 denote hangers of usual construction adapted to be suspended from a conventional derrick (not shown) and having their lower extremities operatively connected with a foot rest or platform 2. Also operatively connected with the lower extremities of the hangers 1 are the supports 3 for the seat structure proper which, as herein disclosed, are disposed outwardly from the hangers and longitudinally of the platform 50 and on which the seats 4—4 are adapted to be rested, such seats having the end

rails 5 thereof provided in their under portions with the notches 6 adapted to engage the cross bars 7 disposed between adjacent end hangers 1 at points above but immediately adjacent the upper portions of the supports 3. Each seat 4 is provided with the back 8 hingedly connected therewith, as indicated at 9, while the back is operatively connected with the adjacent hangers through 65 the medium of the interposed rigid links 10, such links being of a predetermined length so as to determine the distance the seat 4 and its back 8 will assume relative to the platform or foot rest 2 when the seat and its 70 back are swung inwardly in order to afford the bed structure. Each of the seats and its back are of such transverse dimension as to afford a convenient bed structure when swung inwardly, the opposed margins of the 75 seats being adapted to substantially abut when such adjustment is effected and in order that the requisite stability or rigidity may be imparted to the bed structure, I find it of advantage to employ the auxiliary or 80 supplemental members 11 of predetermined length and being provided in their under edges adjacent their extremities with the notches 12 adapted to accommodate the cross bars 7.

In order that the coaction between the seats 4 and the supplemental or auxiliary members 11 with the cross bars 7 may be afforded with a minimum of friction, I find it of advantage to surround such cross bars 90 7 with the sleeves 14 for a purpose which is believed to be clearly apparent to those skilled in the art to which my present invention appertains.

From the foregoing description, it is 95 thought to be obvious that a swing constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this 100 reason I do not wish to be understood as limiting myself to the precise arrangement and formation of the several parts herein shown in carrying out my invention in practice.

I claim:

110 A device of the class described comprising hangers, a platform connected with the

lower extremities of the hangers, supports operatively engaged with said hangers, cross bars connecting the hangers above the supports and in close proximity to the supports, 5 said supports being disposed outwardly relative to the hangers and longitudinally of the platform, seats adapted to rest upon the supports and including end rails provided in their under edges with notches to interlock with the cross bars, backs pivotally engaged with the seats, rigid links operatively engaged with the hangers and the backs, said

links serving to limit the inward movements of the seats and backs, and supplemental members adapted to engage the cross bars 15 and to be positioned below the seats and backs when the same are swung inwardly.

In testimony whereof I hereunto affix my signature in the presence of two witnesses.

ASA I. RABB.
